UNITED STATES PATENT OFFICE.

FRANZ J. HEIBERGER, JR., OF BOSTON, MASSACHUSETTS, AND MARGARET CARTER STUART, OF RICHMOND, VIRGINIA.

SEARCH OR HEAD LIGHT.

1,149,441.

Specification of Letters Patent. Patented Aug. 10, 1915.

Application filed October 23, 1914. Serial No. 868,306.

To all whom it may concern:

Be it known that we, FRANZ J. HEIBERGER, Jr., of the city of Boston, Suffolk county, Massachusetts, and MARGARET CARTER STUART, of Richmond, in the county of Henrico and State of Virginia, have invented certain new and useful Improvements in Search or Head Lights, of which the following is a specification.

10 The present invention relates to the art of headlights or road lights such as are particularly employed on automobiles and road vehicles, to light up the road-way ahead, and the invention particularly has for its 15 object to provide a lamp of this character wherein means are contained for cutting off more or less of the projected light beam, when desired, to prevent blinding pedestrians or others coming from the opposite 20 direction.

In our application filed March 24, 1914, Ser. #826,955, we have disclosed a lamp structure which is adapted for the purposes but in that case no provision was made for 25 special operating mechanism for projecting or retracting the light intercepting member (a shield or series of shields), whereas the present invention especially has for its object to provide electro operative mechanism 30 for effecting the movement of the shield or shields.

Generically, the invention provides a lamp having an illuminant and a reflector and a movable shield or light intercepting member 35 which is designed to be projected to intercept the light beam in whole or in part, and an electric motor driven connection with the shield for projecting or retracting the same at will, together with circuit breakers in the 40 motor circuit which are designed to coöperate with the shield whereby to automatically open the motor circuit as the shield reaches the limits of its movement.

Again, the invention has for its object to 45 provide a combined side and head-light which embodies the foregoing special features.

Another object is to provide a lamp of the foregoing character in which the various 50 parts are easily accessible for inspection or repair and in which the driving mechanism and the circuit breakers may be made acces-

sible without disturbing the arrangement of the reflector, the illuminant or the light beam intercepting shield. 55

More subordinately the invention has for its object to provide a lamp embodying the foregoing characteristics which will be ornamental in appearance, compact, inexpensive in construction, and one which will readily 60 serve its intended purposes.

In its more detailed nature, the invention includes those novel features of construction, combination and arrangement of parts, all of which will be first fully described, and 65 then be specifically pointed out in the appended claims, and illustrated in the accompanying drawings, in which:—

Figure 1 is a perspective view of the invention with the light intercepting shield 70 projected. Fig. 2 is a central vertical longitudinal section of the invention with the parts as normally located. Fig. 3 is an enlarged elevation of the lower circuit breaker. Fig. 4 is an enlarged vertical section of the 75 lower circuit breaker taken substantially on the line 4—4 of Fig. 3. Fig. 5 is a view similar to Fig. 2, showing the parts in the position shown in Fig. 1 with the light intercepting shield projected. Fig. 6 is a section 80 on the line 6—6 on Fig. 7, showing the construction of the upper circuit breaker. Fig. 7 is a side elevation, a part being broken away, of the upper circuit breaker. Fig. 8 is a diagrammatic view of the electric 85 circuits. Fig. 9 is a detail section on the line 9—9 on Fig. 2. Fig. 10 is a perspective view of a modification of the invention. Fig. 11 is an enlarged side elevation and 90 part section of a part of the form shown in Fig. 10.

In the drawings, in which like numerals and letters of reference indicate like parts in all the figures, 1 represents the body of the lamp housing which is provided with 95 the usual supporting ears 2 to receive the fork 3 of the standard and which is also provided with a door 4. The door 4 is hinged to the body 1, as at 5, and is pin-connected at 6, or otherwise suitably secured 100 so as to be susceptible of being opened, as shown in dotted lines in Fig. 2, when it is desired to gain access to the interior of the body 1. The door 4, when the lamp is de-

signed as a combined side and head-light, is provided with an upward extension 7 having a front window 8 and side windows 9, which windows are suitably glazed as at 5 10-11.

12 is the side light reflector that is secured over the window opening 8 within the door 4, and is rigidly supported thereby.

13 is the small candle power illuminant 10 and 14 the mount for the same. The mount 14 has a separable connection with the fixed terminals 15, whereto the circuit wires 25 from the ordinary dash switch (not shown) are connected, it being understood that the 15 terminal block 15 is rigidly secured within the cap 16 of the housing 1. The cap 16 is pivoted at 17 and is connected at 6 with the upward extension of the door 4. The door 4 has a main opening 18 suitably glazed at 19 and provided with a fixed shield 20 to prevent access of water to the interior of the lamp. The glass 19 is held in a suitable frame 26 which is hinged at 27 and secured at 28 so as to be susceptible of being opened 25 up to permit access to the reflector 21 which is also held in place by the frame 26 when closed. The reflector 21 carries the usual bulb mount 22 on which the illuminant bulb 23 is carried and to the terminals of which 30 the current wires 24 from the dash switch (not shown) are connected. It should be understood that the current supplied to the illuminants 13-23 is supplied in the usual manner, and the manner in which the current is supplied to these illuminants forms 35 no part of our present invention and is therefore not illustrated in detail.

29 is the shield or light beam interceptor 40 which may be composed of a skeleton frame and more or less opaque bodies (as in our previous application before referred to) or it may be composed of a single body, if desired. The shield 29 is pivoted at 30 and is provided with a rack 32 and a flange 31, the 45 flange being provided to close the opening in the front of the door 4 through which the shield is adapted to be projected when the shield is retracted. The rack 32 has a heel 33 to coöperate with the lower circuit breaker 52 and a projection 34 to coöperate with the upper circuit breaker 44 in a manner hereinafter more fully explained.

35 is a worm which is mounted in bearings 37-36 that are rigidly secured to and 50 within the door 4, the worm 35 having a separable joint 38 with the drive shaft 39 of the reversible electric motor 40, the latter being mounted rigidly within the housing 1.

41 is a support rigidly mounted, prefer- 55 ably on the motor frame, which carries the relatively fixedly located contact block 43 by means of which the leading-in wire terminals may be brought into electrical connection with the terminals 46-47 of the upper circuit breaker 44.

The upper circuit breaker 44, which is best illustrated in Figs. 6 and 7 of the drawings, comprises a supporting block that is rigidly secured in the bracket 36 and carries a fixed contact plate 45. The plate 45 is 70 electrically connected to the terminal 46, while the terminal 47 is electrically connected to the yieldable contact 49 which is provided with a head 50 to engage the contact 45 under the action of the spring 51. 75

The lower circuit breaker 52 consists of two rigid blocks 53-56, in one of which a rigid contact 54 is held and in the other a yieldable contact 57 is mounted. The contact 54 has a head 55 that is adapted to be 80 engaged by the head 58 of the contact 57 under the action of the spring 51.

The heads 58-50 are adapted to project into the path of movement of the heel 33 and the projection 34, irrespective of the 85 rack 32, whereby when the shield 29 is retracted as shown in Fig. 2, the heel 33 will depress the head 58 to open the circuit between the heads 55-58, while the circuit between the heads 45-50 remains closed, but when the shield is projected to its limit, the member 34 will engage the head 50 to open the motor circuit between head 50 and plate 45, as will be clearly explained.

59 designates the control switch which is 90 provided with an "off" contact 60, an "out" or "down" contact 61 and an "in" or "up" contact 62. The contact 61 is electrically connected with the plate 45 of the upper circuit breaker, while the head 50 of that 100 circuit breaker is connected electrically to the motor 40. The motor 40 is also electrically connected with the head 58 of the lower circuit breaker 52, while the head 55 is electrically connected with the contact 62, 105 as diagrammatically illustrated in Fig. 8, the switch arm 63 of the switch 59 is electrically connected with the battery 64, which battery in turn is connected to the motor, it being understood that the motor wiring 110 and connections are such that when current is passed through the motor via the upper circuit breaker, the motor will turn in one direction while when the current is passed to the motor via the lower circuit 115 breaker, the motor will turn in the opposite direction.

So far as described, when it is desired to project the shield into the beam of light, the operator moves the switch 63 onto the 120 contact 61, which permits the current to flow through the motor in a direction that will cause the worm 35 to turn and move the light from the position shown in Fig. 2 toward the position shown in Figs. 1 and 5. 125

Should the operator desire to move the shield only a slight distance, he makes the contact between 63 and 61 of short duration, but if he desires to project the light the full distance, or should he forget to open 130

the circuit again at the contact 61, as soon as the projection 34 engages the head 50 of the upper circuit breaker, the said head will be pressed back to open the motor circuit at the upper circuit breaker, it being understood, of course, that the spring 51 is preferably light enough so as not to move the shield backwardly and again close the circuit, or in other words, is not sufficiently strong to overcome the weight of the shield.

When it is desired to retract the shield, the operator moves the switch 63 onto contact 62, whereupon the motor is reversed, and as soon as the heel 33 engages the head 58 of the lower circuit breaker, the motor circuit will be automatically opened at that place.

Should the shield be only partly retracted, both circuit breakers will be closed and the shield can be moved farther in either direction according as contact is made between the switch lever 63 and one or the other of the contacts 61-62.

In Figs. 10 and 11 there is shown a modification of the invention in which the motor, the circuit interrupting switches and the shield are all mounted on the door structure. In this form, 65 designates the door, and 66 the shield, the constructions of which may be the same as that disclosed in our preceding application hereinbefore referred to, the shield and door being so designed that the shield may be telescoped entirely within the tubular door structure. In this form of the invention also the lowermost shield section (when the shield is made up of several sections) is provided with the rack 67 with which the worm 68 on the motor shaft 69 meshes, the motor 70 being located in an extension housing 71 carried by the door 65 and the extension housing 71 may be provided with a door 72 by means of which access to the motor may be had for purposes of adjustment or repair. The circuit opening switches 52 and 44 respectively are mounted within the door structure and operated by the projection 73 on the gear segment 67. In this form of the invention, it will be observed, the necessity for separable connections, used in the preceding form, may be dispensed with. This latter form of the invention is especially adapted for attachment to the ordinary lamp by simply removing the old door and substituting the new door with its attached parts.

From the foregoing description, taken in connection with the accompanying drawings, it is thought the complete construction, operation and advantages of the invention will be readily apparent to those skilled in the art.

What we claim is:

1. The combination, in a head or search lamp, with the lamp housing; a shield asso-

ciated with the housing for intercepting the beam of light; a rotary electric motor associated with and supported by the lamp; operative connections between said motor and said shield for effecting the movements of the shield in both directions; an operator manipulated controlling device for the motor; and means for arresting the operation of the motor as the shield reaches the limits of its path of movement.

2. The combination with a head or search lamp and a shield mounted to be moved into and out of the beam of light; of a motor for moving said shield into and out of the beam of light, means for arresting the action of said motor as the shield reaches the limits of its path of movement, and operator manipulated means for effecting the action of said motor on said shield.

3. In a lamp construction, a lamp housing, a reflector in said housing, an illuminant in said housing, a hood or shield carried by said housing, and an electric motor and operating connections between said motor and said hood or shield for moving said shield to intercept the light beam at will, an operating circuit for the motor, and circuit breakers for opening the motor circuit at predetermined times.

4. In a lamp construction, a lamp housing, said housing including an illuminant chamber, a second chamber distinct from said illuminant chamber, a shield mounted in said second chamber, and a rotary motor for projecting and retracting said shield.

5. In a lamp construction, a lamp housing, said housing including an illuminant chamber, a second chamber distinct from said illuminant chamber, a shield mounted in said second chamber, a motor for projecting and retracting said shield, an operator manipulated circuit for said motor, and circuit breakers operatively controlled by the movement of said shield for opening the motor circuit as the shield reaches the limits of its path of travel.

6. A lamp housing, a door therefor, a reflector and an illuminant carried by the door, a light beam intercepting shield also carried by said door, a motor, power transmitting connections between the motor and the shield, and operator controlled means for effecting the action of said motor.

7. A lamp housing, a door therefor, a reflector and an illuminant carried by the door, a light beam intercepting shield also carried by said door, a motor, power transmitting connections between the motor and the shield, operator controlled means for effecting the action of said motor, said means comprising an electric circuit, and means for interrupting said circuit as said shield reaches the limit of its projection.

8. A lamp housing, a door therefor, a reflector and an illuminant carried by the

- door, a light beam intercepting shield also carried by said door, a motor, power transmitting connections between the motor and the shield, operator controlled means for effecting the action of said motor, said means comprising an operator manipulated electric motor circuit. 5
9. A lamp housing, a door therefor, a reflector and an illuminant carried by the door, a light beam intercepting shield also carried by said door, a motor, power transmitting connections between the motor and the shield, operator controlled means for effecting the action of said motor, said means comprising an operator manipulated electric motor circuit, circuit breakers in said motor circuit, and means governed by the movements of said shield for operating said circuit breakers as said shield reaches the limits 10 of its path of movement. 15
10. In a lamp, a housing including a bottom housing section and a top housing section separably mounted on said bottom section, said sections being open at the front, a door fitted over said opening, a window carried by said door, an illuminant within said housing, a shield normally lying retracted in said housing and adapted to be projected therefrom to intercept the beam of light, a 20 motor and a power transmitting connection between said motor and said shield. 30
11. In a lamp, a housing including a bottom housing section and a top housing section separably mounted on said bottom section, said sections being open at the front, a door fitted over said opening, a window carried by said door, an illuminant within said housing, a shield normally lying retracted in said housing and adapted to be projected 35 therefrom to intercept the beam of light, a motor, a power transmitting connection between said motor and said shield, said connection comprising a rack on said shield, and a gear driven by the motor and meshing 40 with said rack. 45
12. In a lamp, a housing including a bottom housing section and a top housing section separably mounted on said bottom section, said sections being open at the front, a door fitted over said opening, a window carried by said door, an illuminant within said housing, a shield normally lying retracted in said housing and adapted to be projected 50 therefrom to intercept the beam of light, a motor, a power transmitting connection between said motor and said shield, said shield being pivotally mounted on said door, and said power transmitting connection comprising a rack on said shield, a 55 worm mounted on said door and meshing with said rack, and a connection between said worm and said motor. 60
13. In a lamp, a housing including a bottom housing section and a top housing section separably mounted on said bottom sec- 65
- tion, said sections being open at the front, a door fitted over said opening, a window carried by said door, an illuminant within said housing, a shield normally lying retracted in said housing and adapted to be projected therefrom to intercept the beam of light, a motor, a power transmitting connection between said motor and said shield, an operator manipulated circuit for said motor, circuit interrupters in said circuit, and means for operating said interrupters by the movements of said shield at predetermined times. 70
14. In a lamp, a housing including a bottom housing section and a top housing section separably mounted on said bottom section, said sections being open at the front, a door fitted over said opening, a window carried by said door, an illuminant within said housing, a shield normally lying retracted in said housing and adapted to be projected therefrom to intercept the beam of light, a motor, a power transmitting connection between said motor and said shield, an operator manipulated circuit for said motor, circuit interrupters in said circuit, and means for operating said interrupters by the movements of said shield at predetermined times. 75
15. In a lamp, a housing including a bottom housing section and a top housing section separably mounted on said bottom section, said sections being open at the front, a door fitted over said opening, a window carried by said door, an illuminant within said housing, a shield normally lying retracted in said housing and adapted to be projected therefrom to intercept the beam of light, a motor, a power transmitting connection between said motor and said shield, said shield being pivotally mounted on said door, said power transmitting connection comprising a rack on said shield, a worm mounted on said door and meshing with said rack, a connection between said worm and said motor, an operator manipulated circuit for said motor, circuit interrupters in said circuit, and means for operating said interrupters by the movements of said shield at predetermined times. 80
16. In a lamp construction, a housing comprising a bottom section, a top section, said sections being open at the front, a door for closing said opening, said door having a window, a reflector mounted on said door in alignment with said window and an illuminant coöperating with said reflector to project a beam of light through said window, a shield pivotally mounted on said door and normally lying invisible within said housing, said shield being adapted to be projected into the beam of light to intercept more or less of the beam, a motor within said housing and power transmitting connections 85

between said motor and said shield for effecting the movements of said shield, and means for actuating said motor.

17. In a lamp construction, a housing comprising a bottom section, a top section, said sections being open at the front, a door for closing said opening, said door having a window, a reflector mounted on said door in alinement with said window and an illuminant coöperating with said reflector to project a beam of light through said window, a shield pivotally mounted on said door and normally lying invisible within said housing, said shield being adapted to be projected into the beam of light to intercept more or less of the beam, a motor within said housing, power transmitting connections between said motor and said shield for effecting the movements of said shield, means for actuating said motor, said door having an auxiliary window, an auxiliary illuminant mounted to project light through said auxiliary window, both of said illuminants being relatively fixedly located with relation to the door whereby when the door is opened said illuminant will move with said door substantially as shown and described.

18. In a lamp construction, a housing comprising a bottom section, a top section, said sections being open at the front, a door for closing said opening, said door having a window, a reflector mounted on said door in alinement with said window and an illuminant coöperating with said reflector to project a beam of light through said window, a shield pivotally mounted on said door and normally lying invisible within said housing, said shield being adapted to be projected into the beam of light to intercept more or less of the beam, a motor within said housing, power transmitting connections between said motor and said shield for effecting the movements of said shield, means for actuating said motor, said power transmitting connections including a rack on the shield, a worm meshing with said rack and a separable connection between said worm and the motor, said illuminant, said reflector, said shield and said worm being relatively fixedly located with relation to said door whereby when said door is removed or opened said last named parts will move as a unit with the door substantially as shown and described.

19. In a lamp structure, a housing having an opening, a door mounted over said opening, a window carried by said door, a reflector carried by said door, an illuminant carried by said reflector for coöperation with the same in projecting a beam of light through said window, a shield of the spherical segment type pivotally mounted on said door and normally adapted to lie within said housing, said shield being adapted to be projected out of said door to more or

less intercept the beam of light, a rack carried by said shield, a worm mounted on the door and meshing with said rack, a motor mounted within said housing, and a separable connection between said motor and said worm, a motor circuit for operating said motor, and a circuit breaker carried by said door for interrupting the motor circuit when said shield has been projected a predetermined amount.

20. In a lamp structure, a housing having an opening, a door mounted over said opening, a window carried by said door, a reflector carried by said door, an illuminant carried by said reflector for coöperation with the same in projecting a beam of light through said window, a shield of the spherical segment type pivotally mounted on said door and normally adapted to lie within said housing, said shield being adapted to be projected out of said door to more or less intercept the beam of light, a rack carried by said shield, a worm mounted on the door and meshing with said rack, a motor mounted within said housing and a separable connection between said motor and said worm, a motor circuit for operating said motor, a circuit breaker carried by said door for interrupting the motor circuit when said shield has been projected a predetermined amount, a second circuit breaker within said housing for interrupting the motor circuit when said shield has been retracted, and means carried by said shield for effecting the action of said circuit breakers.

21. In a lamp construction, a lamp housing having an opening, a door mounted over said opening, a window carried by said door, a reflector carried by said door, an illuminant carried by said reflector, a shield mounted on said door to normally lie invisibly retracted, a rack carried by said shield, a worm meshing with said rack, and an electric motor for driving said worm, electric circuit connections for reversibly operating said motor to thereby project or retract said shield.

22. In a lamp construction, a lamp housing having an opening, a door mounted over said opening, a window carried by said door, a reflector carried by said door, an illuminant carried by said reflector, a shield mounted on said door to normally lie invisibly retracted, a rack carried by said shield, a worm meshing with said rack and an electric motor for driving said worm, electric circuit connections for reversibly operating said motor, to thereby project or retract said shield, and electric circuit breakers coöperating with said motor circuit and with said shield for restraining the operation of the motor as said shield reaches the limits of its path of movement.

23. In a lamp construction, the combina-

tion with a lamp housing and a door, of a shield normally retracted from the beam of light and adapted to be projected into the beam of light, an electric motor, a gear connection between said motor and said shield for projecting and retracting the same, and an operator manipulated electric circuit for operating said motor.

24. In a lamp construction, the combination with a lamp housing and a door, of a shield normally retracted from the beam of light and adapted to be projected into the beam of light, an electric motor, a gear connection between said motor and said shield for projecting and retracting the same, an operator manipulated electric circuit for operating said motor, and circuit breakers actuated by the movements of said shield for interrupting the motor circuit as said shield reaches the limits of its path of movement.

25. In a lamp construction, a lamp housing including a chamber, an illuminant in said housing and a shield in said chamber, a motor in said housing and coöperative connections between said motor and shield for raising and lowering said shield.

26. In a lamp construction, a lamp housing including an illuminant chamber, a shield carried by said housing, a motor carried by said housing for projecting and retracting said shield, an operator manipulated circuit for said motor, and circuit breakers operatively controlled by the movement of said shield for opening the motor circuit as the shield reaches the limits of its path of travel.

27. In a lamp construction, the combination with a lamp housing, of a shield nor-

mally retracted from the beam of light and adapted to be projected into the beam of light, an electric motor, power transmitting connections between said motor and said shield for projecting and retracting the same, an operator manipulated electric circuit for operating said motor, and circuit breakers for interrupting the motor circuit as said shield reaches the limits of its path of movement.

28. In a lamp construction, a lamp housing including a chamber, an illuminant in said housing, a shield associated with the lamp and adapted to be projected into and out of the beam of light, a motor supported by said housing, and coöperative connections between said motor and said shield for actuating said shield.

29. The combination in a head or search lamp, of the lamp housing, a shield for intercepting the beam of light emanating from said lamp housing, a reversible electric motor operatively connected with said shield for effecting the movements of the shield in both directions into and out of the beam of light respectively, and means for automatically stopping the operation of said motor as said shield arrives at the limits of its path of movement.
